UNITED STATES PATENT OFFICE.

LEVI R. HASLETT, OF WINDSOR, VERMONT.

BILL-FILE.

1,195,008.

Specification of Letters Patent. Patented Aug. 15, 1916.

Application filed August 19, 1915. Serial No. 46,302.

To all whom it may concern:

Be it known that I, LEVI R. HASLETT, a citizen of the United States, residing at Windsor, in the county of Windsor and State of Vermont, have invented certain new and useful Improvements in Bill-Files; and I do hereby declare the following to be a full, clear, and exact description of the invention, such as will enable others skilled 10 in the art to which it appertains to make and use the same.

The invention relates to improvements in bill files.

The object of the present invention is to 15 improve the construction of bill files and to provide a simple, practical and inexpensive bill file of strong and durable construction adapted to present an ornamental appearance and designed for use in offices and various other places where it is desirable to 20 file safely memoranda, bills, sales checks, etc., and capable of enabling any of its contents to be easily and quickly removed without removing any of its contents not desired.

With these and other objects in view the 25 invention consists in the construction and novel combination and arrangement of parts hereinafter fully described, illustrated in the accompanying drawings and pointed 30 out in the claims hereto appended, it being understood that various changes in the form, proportion and minor details of construction may be resorted to without departing from the spirit or sacrificing any of the 35 advantages of the invention.

In the drawing Figure 1 is a side elevation of a bill file constructed in accordance with this invention, the operating handle being in section, Fig. 2 is a plan view of the 40 bill file, Fig. 3 is an end elevation of the same, Fig. 4 is an enlarged detail sectional view illustrating the manner of mounting the pivoted or swinging member or rod, Fig. 5 is an enlarged vertical sectional view 45 illustrating the construction of the interlocking section between the fixed and movable rods or members, Fig. 6 is an enlarged horizontal sectional view of the same.

Like numerals of reference designate corresponding parts in the several figures of the drawings.

In the accompanying drawings in which is illustrated the preferred embodiment of the invention, 1 designates a substantially oblong base preferably consisting of a hollow casting composed of two substantially

concavo convex portions 2 and 3 connected together at 4 but the base may be made of any other desired configuration as will be readily understood.

The form illustrated in the drawing, however, is preferable as it provides a stable bill file which is not easily overturned. The hollow casting is provided with a flat bottom 5 constructed of sheet metal or other suitable material and interlocked with grooves or notched portions 6 at the interior of the hollow base adjacent to the lower edges thereof. Any suitable construction may be employed for this purpose and the 70 horizontal bottom, which is designed to be provided with a covering 7 of felt or other suitable material may be secured to the base in other desired manner. The concavo-convex portion 2 which is larger than the 75 other portion 3 of the base has rigidly secured to it a fixed vertical rod or member 8 and the base is provided with a vertical tubular extension 9 rising from the center of the concavo-convex portion 3 and provided 80 with a bore or opening 10 for the reception of a pivoted or laterally swinging rod or member 11 which has a curved connecting arm or portion 12 adapted to engage and interlock with the upper end of the fixed 85 rod or member 8. The lower end of the vertical rod or member 8 may be secured to the base in any desired manner and its upper end 13 is tapered and is provided with opposite grooves 14 and 15 located at the front 90 and back of the fixed rod or member 8 and forming side portions 16 and 17 of unequal widths, the right hand side portion 17 being of greater width than the left hand side portion 16 and adapted to form a stop 95 for limiting the lateral swing of the arm or connecting portion 12 of the movable rod or member 11. The end of the movable rod or member at the terminal of the arm 12 is forked to form prongs 18 which straddle the 100 tapered end of the fixed section or member 8 and fit in the front and rear grooves 14 and 15.

The prongs 18 have rounded inner faces 19 which fit snugly in the grooves and the 105 latter are curved transversely to present concaved faces to the prongs. The prongs are seated in the grooves and straddle and interlock the pointed ends of the fixed rod or member 8 and are maintained yieldably 110 in engagement with the same by a coiled spring 20 and a smooth connection is formed

between the fixed and movable rods or members so that bills, memoranda, sales checks and the like may be readily transferred from one member to the other in placing them on 5 and in removing them from the bill file.

The spring 20 which is mounted on the lower portion of the movable rod or member 11 is interposed between the top of the hollow base and a nut 21 but any other suitable 10 stop may of course be employed and the nut after being placed on the rod may be riveted to prevent it from coming off. The spring 15 holds the curved connecting arm 12 firmly in interlocked relation with the fixed rod or member 8 but the curved engaging faces enable the movable rod or member to be readily swung into and out of engagement with the pointed upper end of the fixed rod or member.

20 The movable rod or member is adapted to be operated by an arm secured to the rod or member 11 and extending outwardly through a horizontal slot 23 in the lower end of the tubular extension and carrying 25 a head 24. The tubular extension is provided at the ends of the slot 23 with notches 26, the notch 26 being slightly deeper than the notch 25 and the bottom wall thereof being slightly spaced from the operating 30 arm when the curved connecting arm 12 is in engagement with the tapered upper end of the fixed rod or member 8 to enable the spring to act directly upon the rod 11 and maintain the curved arm 12 in positive engagement with the fixed rod 8 by spring 35 pressure.

The operating arm and the knob or head are in convenient position to be readily operated by placing the thumb against the 40 tubular extension and the forefinger against the knob or head and a relatively slight movement of the operating arm will open and close the movable rod or member. The bill file is operated in the ordinary manner 45 by opening the connecting arm 12 and placing the bills or other memoranda on the rod or member 8. The curved arm is then moved to its closed position and the bills and other memoranda on the rod or member 8 are then 50 moved to the other rod or member 11. The contents of the bill file are quickly moved from one side or rod or member to the other and any bill or memorandum may be quickly removed without removing any but the matter wanted. The walls of the notches yieldably hold the movable member against pivotal or lateral movement and as they are curved they will permit the operating arm 55 to readily ride out of them. The pivoted or movable arm is held in its open and closed 60 position and the device may be readily carried by the curved connecting arm or portion in handling the bill file or carrying it from

one place to another without the bill file accidentally opening. The vertical tubular 65 extension 9 besides forming a bearing for the pivoted or swinging member of the bill file also serves to support bills and other papers at an inclination, the upper end of the pile of papers resting upon the top of 70 the tubular extension and the inclined position of the papers causing more or less of a separation of the same and facilitating a quick examination of the contents of the bill file. 75

What is claimed is:—

1. A bill file including a base, a fixed rod, a tubular extension projecting upwardly from the base and having a horizontal slot provided with opposite notches, a movable rod mounted in the tubular extension and provided with an operating arm extending through the said slot, said movable rod being also provided with a connecting arm for engaging the fixed rod, and a spring connected with the movable rod for yieldably holding the same in engagement with the fixed rod, the operating arm being out of engagement with the bottom of the notch when the connecting arm is in engagement 90 with the fixed rod or member.

2. A bill file including a fixed rod having a tapered upper end and provided thereat with opposite grooves and a movable rod having a connecting arm provided with a 95 forked terminal straddling the tapered end of the fixed rod and engaging the grooves thereof.

3. A bill file including a fixed rod having a tapered upper end and provided 100 thereat with opposite grooves and a movable rod having a connecting arm provided with a forked terminal straddling the tapered end of the fixed rod and engaging the grooves thereof, the grooves of the fixed 105 rod being transversely concaved to present concaved faces to the forked portion of the arm and the prongs formed by the fork being rounded at their inner faces.

4. A bill file including a fixed rod having a tapered upper terminal and provided with opposite grooves forming side portions of unequal widths, the wider side portion constituting a stop and a movable rod having a connecting arm provided with a 115 forked terminal straddling the tapered end of the fixed rod and engaging the grooves thereof and limited in its lateral movement by the said stop.

In testimony whereof I affix my signature 120 in presence of two witnesses.

LEVI R. HASLETT.
